ATTORNEY.

UNITED STATES PATENT OFFICE

CHARLES D. VLAHEK, OF EAST ST. LOUIS, ILLINOIS

METHOD OF AND MEANS FOR RENEWING VALVE SEATS

Application filed August 9, 1929. Serial No. 384,737.

This invention relates to valve seats and methods of making the same, and more specifically to the renewing of worn valve seats in internal combustion engines.

5 In large internal combustion engines, such as are used in trucks, buses, etc., the valve seats are subject to intense wear, and in the course of time the valve seats will no longer perform their function. It is then necessary to renew the worn valve seats. This is usually done by removing the cylinder head containing the worn valve seats and substituting a new cylinder head with its new valve seats. This practice, however, is extremely 15 expensive, and as a result various attempts have been made to replace the worn valve seats with new valve seats. However, prior to this invention these attempts have not proved entirely successful because the new 20 valve seats were not properly held in place. The strain on the valve seats is so intense that the new valve seats would be jarred out of place and in some cases cause serious damage by falling into the moving parts of the 25 engine. Consequently the expensive practice of replacing the cylinder block, the head, or at least the valve chamber, has been regarded as the only safe method.

The main object of this invention is to 30 replace a worn valve seat with a simple and relatively inexpensive new valve seat which is securely and positively held in place, so that it will not be loosened during the operation of the engine.

35 With the foregoing and other objects in view, the invention comprises the novel method, construction, combination and arrangement of parts hereinafter more specifically described and illustrated in the accompanying drawing, wherein is shown the preferred embodiment of the invention. However, it is to be understood that the invention comprehends changes, variations and modifications which come within the scope 40 of the claims hereunto appended.

Fig. 1 is a section illustrating a portion of an internal combustion engine equipped with a valve seat embodying the features of this invention.

45 Fig. 2 is a top view on a larger scale show-

ing the valve seat and a portion of the valve chamber.

Fig. 3 is an enlarged section taken on the line 3—3 in Fig. 2.

Fig. 4 is a top view of the valve seat.

Fig. 5 is a top view of the locking member which secures the valve seat.

1 designates the valve chamber of an internal combustion engine. The valve stem 2 is located in a guide 3 and the head 4 of the valve is adapted to rest on a valve seat member 5 which has a face 6 to receive the head 4.

The valve chamber 1 is provided with a circular recess providing a circular wall 7 and an abutment shoulder 8. The valve seat member 5 is in the form of a ring seated upon the abutment shoulder 8 and has its peripheral face 9 in frictional engagement with the circular wall 7 of the recess. The peripheral face of the valve seat member and the circular wall 7 of the recess are provided with annular grooves 10 and 11 which register with each other and have substantially flat parallel upper and lower walls.

A flexible locking member 12 in the form of a spring ring having substantially flat upper and lower faces is located in the grooves 10 and 11 to secure the valve seat 5 in the recess. This ring is cut transversely to provide the separated ends shown in Fig. 5.

Since the valve seat member 5 contacts with abutment shoulder 8, the shocks resulting from hammer blows delivered from the valve to the valve seat member are transmitted to said abutment shoulder. The locking ring is, therefore, relieved of these shocks. This locking ring cannot be released nor in any way impaired by the severe shocks and vibrations or changes in temperature to which the valve seat member is subjected.

The method of locating the valve seat 5 and the locking means in the valve chamber will now be described. The worn valve seat (not shown) is removed to form a circular recess. This may be accomplished by boring out the old valve seat.

The annular groove 11 is then formed in the circular wall of the recess. The valve seat member 5 is formed in the shape of a

ring to conform to the recess, and the annular groove 10 is formed in the peripheral face of the valve seat member.

The portion of the valve chamber surrounding the circular recess is heated to expand the metal and thus enlarge the recess. The valve chamber is preferably heated by steam because there is no danger of overheating the metal of the valve chamber when steam at its ordinary temperature is used for this purpose.

The spring ring is placed in the annular groove 10 in the peripheral face of the valve seat, and contracted to be entirely within the annular groove. The valve seat while relatively cold with the contracted spring ring is then located in the recess, and the spring ring will expand when it registers with the annular groove 11 so that it will be locked in both of the annular grooves. The valve seat will then be securely held in place.

I claim:

1. The method of renewing a worn valve seat in a valve chamber which comprises forming a recess in the valve chamber at the worn valve seat, heating that portion of the valve chamber surrounding said recess, with steam at substantially its ordinary temperature, placing a relatively cold valve seat in said recess, and at the same time locating a yieldable locking member between the wall of said recess and said valve seat to secure said valve seat in said recess.

2. The method of renewing a worn valve seat in a valve chamber which comprises removing the worn valve seat to form a circular recess, forming a valve seat in the shape of a ring, forming annular grooves in the circular wall of said recess and in the peripheral face of said valve seat, locating a spring ring in the annular groove in said valve seat, heating that portion of the valve chamber surrounding the circular recess with steam at substantially its ordinary temperature, and placing the valve seat, while relatively cold, with the spring ring in said recess so that the spring ring is locked in said annular grooves.

3. A valve chamber having a circular recess, a valve seat in the form of a ring having its peripheral face in frictional engagement with the circular wall of said recess, said peripheral face and circular wall being provided with annular grooves registering with each other and having substantially flat parallel upper and lower walls, and a spring ring located in said grooves to secure the valve seat in said recess, said spring ring having substantially flat upper and lower faces in contact with the respective flat upper and lower walls of said annular grooves.

In testimony that I claim the foregoing I hereunto affix my signature.
